UNITED STATES PATENT OFFICE.

JAMES G. SCHOOLEY AND HENRY M. RANSDELL, OF TULSA, OKLAHOMA.

APPARATUS FOR TURNING DEEP-WELL BITS WHEN BEING SHARPENED.

Application filed August 31, 1921. Serial No. 497,189.

To all whom it may concern:

Be it known that we, JAMES G. SCHOOLEY and HENRY M. RANSDELL, citizens of the United States, and residents of Tulsa, in the county of Tulsa and State of Oklahoma, have invented certain new and useful Improvements in Apparatus for Turning Deep-Well Bits When Being Sharpened, of which the following is a specification.

10 This invention relates to an apparatus for turning deep well bits when being sharpened.

As is well known a bit of the type employed for drilling deep wells is heavy and cumbersome. When sharpening the pointed ends of such a bit as a whole must be turned upon the anvil in order that the proper presentation is had. The bit is hot and burdensome and difficult to turn. With this in view it is the object of the present invention to provide means whereby the turning of a bit upon the anvil may be easily accomplished with a minimum of labor and without the possibility of being burnt.

25 It is also an important object of the invention to provide a novel pulley particularly adapted to be used in conjunction with the apparatus.

Other objects will hereinafter appear in 30 the detail description to follow.

The invention is exemplified in the accompanying drawings in which:—

Figure 1 is a diagrammatic view illustrating the invention applied.

35 Figure 2 is a side elevation of the pulley.

Figure 3 is a vertical sectional view of the same.

Figure 4 is a detail view illustrating the particular shape of the groove of the pulley.

40 Referring to the drawings more particularly, 10 indicates an anvil and 11 a bit of the type employed for drilling deep wells. The end of the bit to be sharpened is supported upon the anvil 10 while its other end

45 is supported upon a block 12. The bit is held against longitudinal movement in one direction by a block 13, said block being braced as at 14. About the bit 11 there passes a chain loop 15, said chain also passing about the pulley generally indicated by

the reference numeral 16, and connected to a hook 17 which is in turn suitably connected to a chain fall not shown.

The pulley 17 comprises a sleeve 18 which has formed in its periphery a groove or channel 19. Also upon each side of the groove 19 there is formed a plurality of recesses 20 which are arranged in registering pairs as shown. The sleeve 18 is otherwise fitted upon a squared portion 21 of the shaft 22. The shaft is also formed with the journal portions 23, a collar 24, and a square end portion 25. A U-shaped support 26 is provided and near the terminal ends thereof the sleeve supporting shaft 22 is journaled as shown. The collar 24 holds the shaft against longitudinal movement in one direction and the same being held against movement in the opposite direction by a washer 27' and pin 28'. The U-shaped member affords a convenient means for connecting the pulley 16 to the chain fall as shown. Also the squared end portion 25 of the shaft has fitted thereon a handle 27 consisting in a bar having a central offset portion 28 which is enlarged and provided with an opening adapted to receive the squared end of the shaft 22.

In the operation of the apparatus the same is arranged as shown in Figure 1. The portion of the chain 15 passing over the sleeve 18 has alternate links disposed in pairs of recesses 20 while the remaining links passing over the same are disposed in the groove 19 as shown in Figure 3. As is obvious by this arrangement the chain cannot slip upon the sleeve and thus with the rotation of the pulley the chain must move in a similar direction. When it is desired to turn the bit 11 the same is raised as shown by the chain fall and then the handle 27 is rotated for turning the bit 11 in the desired direction.

We claim:

A pulley, comprising in combination, a U-shaped supporting member, a shaft journaled between the terminals of said supporting member, said shaft having one end extended and a squared portion occurring intermediate the terminals, a sheave fitted upon said squared portion of the shaft and

having a peripheral groove adapted to receive links of a chain and hold the same against sliding movement thereon, a collar upon the extended end of the shaft and adapted to hold the same against longitudinal movement in one direction, a cotter pin carried upon the other end of the shaft

adapted to hold the same against movement in the opposite direction, and a bar secured upon the extended end of the shaft extending transversely thereof whereby said sheave may be rotated. ¹⁰

JAMES G. SCHOOLEY.
HENRY M. RANSDELL.
